UNITED STATES PATENT OFFICE.

JOHN F. MONNOT, OF NEW YORK, N. Y., ASSIGNOR TO DUPLEX METALS COMPANY, OF NEW YORK, N. Y., A CORPORATION OF NEW YORK.

FURNACE.

No. 901,986.

Specification of Letters Patent.

Patented Oct. 27, 1908.

Application filed November 18, 1906. Serial No. 343,248.

To all whom it may concern:

Be it known that I, JOHN F. MONNOT, a citizen of the United States, residing at New York, in the county of New York and State of New York, have invented certain new and useful Improvements in Furnaces; and I do hereby declare the following to be a full, clear, and exact description of the same, such as will enable others skilled in the art 10 to which it appertains to make and use the same.

My invention relates to improvements in furnaces, and particularly to that type thereof wherein heating chambers such as 15 crucibles, more especially very large crucibles, and like objects, are to be heated to a very high temperature by means of a flame jet, such for example as that from an oil or gas burner.

20 My invention consists in means for distributing the flame and heat with approximate uniformity around the heating chamber or crucible or like object, so as to heat the same with approximate uniformity on 25 all sides; in means for radiating heat down upon the metal in such heating chamber while protecting the metal against contamination; and in other features of invention as more fully hereinafter set forth.

30 The objects of my invention are to obviate the uneven heating heretofore characteristic of gas or oil crucible furnaces and the like; to prolong the life of the crucibles or like objects and avoid local over-heating 35 and burning out thereof; to distribute the flame and heat with substantial uniformity around the crucible or like object to be heated; to heat molten metal and the like to very high temperatures; to avoid contamination of the metal while heating the 40 same from the surface; to adapt the furnace for the introduction of articles into the molten metal without contamination of or injury to either such articles or the molten 45 metal itself; and generally to produce a furnace which, while capable of heating crucibles and like articles and the contents thereof to very high temperatures, shall be simple, easy to operate, economical of fuel, and 50 easy to construct and maintain.

In the heating of large crucibles and molten metal contained therein to high temperatures, I have found it exceedingly difficult to avoid local over-heating of the crucibles 55 by the methods heretofore known, while ob-

taining the desired high temperatures, and have found that the crucibles have only a relatively short life, their walls being oxidized and eaten away rapidly under the action of the intense flame.

Furnaces for heating large crucibles usually comprise a chamber lined with fire-brick, of size adapted to receive the crucible and still maintain space between the crucible and the walls of the chamber for the circulation of flame gases and products of combustion. Heat is produced by a flame jet projected into said chamber from a gas or oil burner. The flame jet must not be allowed to play directly upon the crucible, of course, and various attempts have been made to diffuse or scatter the flame; but I have found that even heating of the crucible is impossible by the means hitherto employed ordinarily for this purpose, local overheating taking place at some point, with the result that the crucible soon weakens there and breaks; and it may easily, and does frequently, happen, that while the crucible is overheated at some one point, the crucible as a whole and its contents are not heated hot enough to produce the desired high temperatures. If the flame jet be split by a plow or divider and caused to flow around the crucible, the highest temperature is developed at the back of the crucible, where the divided flame currents come together again, and the crucible is exceedingly apt to fail at this point after a very short period of use. To overcome these difficulties, I have provided reflecting surfaces in the direct line of impingement of the flame or in the path of diverted or reflected portions of the flame, whereby any desired portion of the flame may be reflected back, or to one side, or in any direction desired, against the sides of the furnace chamber and from thence toward or around the crucible. And I have further provided, in the rear portion of the furnace chamber, reflecting surfaces for reflecting back from such portion of the furnace, where there is apt to be an excess of flame gases, portions of the flame gases, and so distributing such flame gases to those portions of the furnace chamber where otherwise the heating effect would be less than is desirable.

Thereby I have been able to obtain substantially uniform heating and to heat both the crucible and its contents to a very high temperature without local over-heating and

with very material lengthening of the life of the crucible for this reason.

I may also provide means for performing a considerable portion of the heating of the 5 contents of the crucible by heat radiated down from a refractory roof through a body of inert gases by which the metal is protected from contact with the flame gases.

The accompanying drawings illustrate certain 10 forms of crucible furnaces embodying my said invention.

In said drawings: Figure 1 shows a horizontal section of a crucible furnace constructed in accordance with my invention, 15 the section being taken below the bottom of the crucible, on the line 1—1 of Fig. 2. Fig. 2 shows a central vertical section of such furnace, on the line 2—2 of Fig. 1. Fig. 3 shows a front elevation of the flame 20 distributor of my furnace. Figs. 4 and 5 are sectional views of an alternative form of furnace embodying the same principles, Fig. 4 showing a horizontal section through the cover of the furnace on the line 4—4 of Fig. 5, and Fig. 5 showing a central vertical 25 section of said furnace. Fig. 6 is a view similar to Fig. 4, but illustrates the use of separate burners for the upper part of the furnace; and Fig. 7 is a central vertical section of the upper part of a furnace provided with such separate burners. Fig. 8 is a horizontal section through the lower part of the furnace shown in Figs. 4 and 5, and illustrates particularly the stepped reflecting surfaces 30 in the back wall of the combustion chamber. Fig. 9 shows an outside elevation of the furnace, and in particular indicates means for raising and lowering the isolating sleeve.

Referring first to Figs. 1 to 3 inclusive, illustrating my furnace in its simplest form, 40 1 designates the furnace walls inclosing the combustion chamber 2, and 3 designates a crucible within said chamber, resting upon a pedestal, and having a flange 5 luted to the walls 1 so as to form a substantially tight joint. The said crucible, when in use, 45 is commonly kept covered by a cover 6 except when it is necessary to obtain access to the crucible.

7 designates a burner adapted to project a flame jet through a port 8 into the combustion chamber 2. This flame jet does not impinge upon the crucible itself, but upon 50 a distributor 9, which also forms the pedestal for the crucible. The flame jet, striking this pedestal, is caused to divide and pass therearound in two streams. I have found, however, that the mere division of a flame in this 55 manner, so that it will flow around beneath the base of the crucible, is not enough to insure even heating of the crucible; but to the contrary, that where the divided currents meet, a zone of intense temperature is produced, 60 unless other means be provided to effect a

further diffusion and distribution of the flame gases. To this end, I provide the distributor or pedestal 9 with a plurality of reflecting faces or facets, against some of which portions of the flame will impinge directly and will be reflected thereby against the walls of the chamber 2 or against other facets and re-reflected therefrom; some of these facets being arranged to reflect the flame impinging thereupon just to the right and left of the entrance port 8, others to reflect other portions of the flame still farther to the right and left, and so on; the portions of the flame so reflected against the walls of chamber 2 being in turn reflected 75 therefrom toward the sides, or upward, or both toward the sides and upward, according to the angle of impingement. The first of these facets of pedestal 9 is a rounded nose 10, designed to receive the direct impingement of the central portion of the flame jet, and to divide said jet into two currents, causing same to flow around the sides of said pedestal. The upper portion 80 10^a of this nose is inclined, and besides dividing the upper portion of the flame, reflects a portion thereof against the wall of chamber 2 just above the entrance port 8; from which wall such portions of the flame are in turn reflected upward toward and 85 along the front of the crucible.

On either side of nose 10 is a facet 11, designed to receive direct impingement of side portions of the flame and to reflect the flame so impinging against the wall of chamber 2, 90 to right and left of entrance port 8, and also to receive portions of the flame reflected from nose 10 and reflect same still farther to the right and left of the entrance port. The upper portions of facets 11 are inclined 105 surfaces or facets 11^a, which reflect the flame striking thereon upward as well as toward the sides of the chamber. The portions of the flame reflected from facets 11 against the sides of the chamber are in turn reflected 110 toward the sides of said chamber. During these successive reflections the branches of the flame affected are of course expanding and rising; moreover the direction of such branches is affected greatly by the currents 115 of flame gases which have not been reflected but are flowing around the pedestal, for which reason the distribution of the flame cannot be predicted exactly on the lines of optical reflection, but on the other hand the 120 interference between the various flame currents and branches thus produced in itself tends to keep a considerable portion of the flame within the front and side portions of the combustion chamber and so to distribute 125 the heating effect as desired.

The portions of the flame reflected from facets 11^a are subject to re-reflection, expansion, and interference with other flame currents flowing around the pedestal and base 130

of the crucible in much the same manner, but are reflected above those portions of the flame reflected from facets 11, and so heat the portions of the crucible to the right and 5 left of the front, but not far from the front. Other facets 12, 12, and 13, 13, reflect other portions of the flame in a similar manner. There may, in fact, be as many of these facets, as desired, and they may be arranged 10 in various different ways. The arrangement of facets shown in the drawings is one which has been found to give very even distribution of the flame.

Owing to the space afforded for expansion 15 and combustion of the fuel, and the very perfect mingling of fuel and air due to interference between different currents, swirls, and the like, the bulk of the combustion will be complete before the flame reaches the 20 vicinity of the sides of the crucible, and the flame gases will be so loaded down with CO_2 , that relatively little combustion of the material of the crucible itself will occur, and for this reason alone the life of the crucible will 25 be greatly increased; but the very effective distribution of the flame produced by the reflection and re-reflection of different portions of it, as described, preventing overheating of any part of the crucible, is also a most potent 30 factor in prolonging the life of the crucible. Furthermore, much of the heat energy of the flame is reflected as radiant energy or heat from the walls of the chamber 2, such heat being very effective so far as the heating of 35 the crucible is concerned, but of course not tending in itself to oxidize or wear away the walls of the crucible. In fact, there is no direct contact of the flame with the walls of 40 the crucible until combustion is so nearly complete that the destruction of the crucible walls will be very slow. To prevent direct contact of the flame with the walls of the crucible before combustion is nearly completed, I make the upper portion of the pedestal 9, 45 above the facets mentioned, a flaring deflector 14. Further, to scatter the gases at the extreme back of the furnace I provide a baffle lug 15, which prevents the bulk of the two flame currents meeting at the back of the furnace until well above the bottom of the crucible. The flame gases escape through ports 16.

A very good flame distribution may be obtained by merely providing facets in the pedestal itself as shown in Fig. 1, 2 and 3. But 55 a still better distribution may often be obtained by providing somewhat similar facets 17 in the rear wall of the combustion chamber 2, as indicated in Figs. 5 and 8; these latter facets being commonly produced by causing certain of the bricks of the lining of the combustion chamber to project out farther than others. It is not so essential to arrange 60 these facets according to a definite system as is the case with the facets at the front of the crucible, as the purpose of the rear facets 17

is rather to break up the flame currents and reflect considerable portions thereof forward or to the sides, with a view to causing interference of flame currents at points well around toward the sides of the chamber instead of at the extreme back thereof. 70

The material of which crucibles must be formed is well known to be a very poor heat conductor, and for this reason it is desirable to supplement the transmission of 75 heat through the crucible walls, by heating from the surface of the body of metal in the crucible. Many metals, however, are subject to excessive deterioration by the action of the flame gases and other gases present in 80 the combustion chamber; and this is especially the case, with certain metals, when said metals are heated far above their melting points. In Figs. 4-7 inclusive I illustrate means whereby such surface heating 85 may be effected by radiation of heat from a refractory roof without direct contact of the flame and furnace gases with the molten metal, such metal in fact, being protected from such contact by a body of inert gas 90 through which, however, radiated heat passes freely. In these figures, 19 designates a cover for the furnace, lined with refractory material and inclosing above the 95 crucible a heating chamber 20 the roof of which is the surface of the refractory lining of cover 19. Near the center of this chamber is an annular space 21 from which lead escape passages 22; and for obtaining access to the interior of the crucible for charging or 100 other reasons and for introducing articles into the molten metal, I provide a sleeve 23 of refractory material.

In the construction shown in Figs. 4 and 5, ports 24 are provided in the walls 1, 105 registering with other spiral ports in the cover 19, and arranged to conduct flame gases from chamber 2 and project same obliquely and approximately tangentially against the roof of the combustion chamber 110 20, such gases being thereby caused to swirl around in said chamber along the surface of such roof, finally passing into the annular exit space 21 and thence out. A body of inert gases (consisting substantially, if not 115 entirely, of CO_2), will collect in the lower part of this chamber 20 and just above the surface of the molten metal; and such inert gases do not have a particularly detrimental influence on many molten metals, while they 120 do serve to exclude air, or other oxidizing gases, and CO and hydrogen, or hydrocarbons (if any) as well as nitrogen, which gases have a curiously detrimental influence upon many metals. But while the flame 125 gases do not reach the molten metal, the heat produced by them is radiated from the roof of chamber 20 downward through the body of inert gases in the lower part of the 130 said chamber to the surface of the molten

metal, thereby effecting surface heating very efficiently.

In the form shown in Figs. 6 and 7, instead of projecting flame gases from the lower chamber 2 into chamber 20, I provide separate burners 26 arranged to project flame jet through ports in cover 19 against the roof of chamber 20.

For various reasons it is desirable that the sleeve 23 should be adjustable vertically. It is preferable that the lower edge of said sleeve shall not project down into the molten metal, at least to any considerable distance, but on the other hand, the sleeve should be able to follow the molten metal; also, when heating up, this may be done most efficiently by raising the sleeve to, or near, the top of chamber 20. Therefore, I arrange this sleeve to move vertically, as indicated in Fig. 9, providing a pivoted lever 27 connected to said sleeve by links 28, and carrying a counterweight 29.

In another application for Letters Patent, filed Dec. 26, 1905, No. 293,409, I have claimed the isolating sleeve 23, and therefore I do not claim the same broadly herein.

What I claim is:—

1. A flame heated furnace provided with flame producing means and comprising a furnace chamber and, within the same, a body of refractory material having a plurality of reflecting faces arranged in steps laterally, one behind the other, said stepped faces being in impinging relation to the flame from said flame-producing means.

2. A flame heated furnace provided with flame producing means and comprising a furnace chamber and, within and near the base of said chamber, a faceted face of refractory material having stepped lateral facets, a plurality of said facets being in impinging relation to the flame from said flame producing means and the facets being so placed with regard to the furnace chamber walls as to cause an approximately uniform upward movement of flame gases in said chamber.

3. A flame-heated furnace provided with flame-introducing means and a support for a heating chamber, said support at its base being provided with faces having facets at different angles and said faceted faces being in impinging relation to the flame produced by said flame-introducing means.

4. A flame heated furnace provided with flame introducing means and a support for a heating chamber having an overhanging upper edge and a faceted base thereunder in impinging relation to the flame produced by said flame introducing means.

5. A flame heated furnace provided with flame introducing means and a support for a heating chamber having an overhanging upper edge and a faceted base thereunder in impinging relation to the flame produced

by said flame introducing means, the facet in the direct line of said flame being rounded.

6. A flame heated furnace provided with flame introducing means and a support for a heating chamber having an overhanging upper edge and a faceted base thereunder in impinging relation to the flame produced by said flame introducing means, the facet in the direct line of said flame being rounded, and its upper portion forming a reentrant angle with the overhanging edge.

7. A flame heated furnace provided with flame introducing means and with a faceted pedestal adapted to support a heating chamber therein, the facet in the direct line of impingement of the flame being rounded and adjoining facets on either horizontal side being plane-surfaced.

8. A flame heated furnace provided with flame introducing means and with a faceted pedestal adapted to support a heating chamber therein, the facet in the direct line of impingement of the flame being rounded and the facets on either horizontal side being plane-surfaced, each successive side facet being shorter horizontally than the one preceding.

9. In a flame heated furnace, a support of refractory material for a heating chamber, said support provided with angularly related facets in its forward side and a rounded rear side.

10. In a flame heated furnace, the combination of a furnace casing of refractory material, means for introducing flame therein, a support for a heating chamber within said casing having a faceted face in line with said flame introducing means, and a flame-diverting body in the interior of the casing behind said support.

11. A flame heated furnace comprising a furnace chamber, means for introducing flame thereinto, a support for a heating chamber in impinging relation to the flame produced by said flame introducing means, said support being faceted to cause even distribution of flame around the heating chamber, and means for introducing heat at a point above the heating chamber and out of impinging contact with the top thereof.

12. In a furnace, a flame chamber, a heating chamber therein, flame introducing means for the flame chamber and means for introducing hot gases above the heating chamber but out of contact with the top of said heating chamber.

13. In a furnace, a flame chamber, a heating chamber therein closing the top of the flame chamber but spaced away from its walls, an arched furnace cover above the heating chamber and one or more burners for directing hot gases against the arch in heat radiating relation to the top of the heating chamber but out of direct contact with such top.

14. In a furnace, the combination of a casting, a heating chamber suspended therein and closing the top of the same, and a removable cover above said heating chamber, 5 said casing and cover having coöperating passages in their walls adapted to abstract hot gases from the space around the heating chamber and deliver same next the roof formed by said cover.
- 10 15. A furnace comprising a flame chamber, a heating chamber therein, a removable furnace cover above the heating chamber, and a sleeve arranged to extend down through the cover toward and into the top of said heating chamber.
- 15 16. A furnace comprising a flame chamber, a heating chamber therein, and a cover above the heating chamber and provided with a sleeve arranged to extend down through it 20 toward the top of said heating chamber, said cover having also means for passing hot gases along its roof and an annular space around said sleeve for the escape of such gases.
- 25 17. In a flame heated furnace, a furnace chamber, means for introducing flame therein and a flame-diverting element projecting upwardly from the floor of the chamber in line with the flame so introduced and provided with a plurality of stepped lateral reflecting facets.
- 30 18. In a flame heated furnace, a furnace chamber, means for introducing flame therein, and a flame-diverting element projecting upwardly from the floor of the chamber in line with the flame so introduced and having flame passages around it, said element being provided with faceted faces, certain of the faces being substantially vertical and others 35 inclined from the vertical.
- 40 19. In a flame heated furnace, a furnace chamber, means for introducing flame therein, and a flame-diverting element projecting upwardly from the floor of the chamber in line with the flame so introduced and having flame passages around it, said element being provided with facets, certain of which are substantially vertical, others inclined from the vertical, and one of which is a curved 45 dividing facet.
- 45 20. A furnace comprising a furnace chamber and flame diffusing and distributing means therein spaced away from the walls of such chamber and adapted to have flame 55 directed thereagainst and comprising a series of reflecting facets arranged to receive the impingement of said flame and to reflect same against the walls of said chamber.
- 50 21. A furnace comprising a furnace chamber and flame diffusing and distributing means therein spaced away from the walls of such chamber and adapted to have flame directed thereagainst and comprising flame dividing means and flame-distributing facets
- arranged to project portions of the flame 65 approximately transversely of the natural flow of flame past said diffusing and distributing means.
22. A furnace comprising flame introducing means, a furnace chamber, and flame 70 diffusing and distributing means therein and spaced away from the wall of such chamber located in the path of the flame so introduced and comprising faces having a plurality of facets in the path of initial projection 75 of said flame, arranged to project portions of the flame toward the walls of said chamber.
23. A furnace comprising flame introducing means, a furnace chamber, and within 80 said chamber and in the path of said flame a flame distributor provided with a flame-dividing portion and on either side thereof flame-reflecting facets arranged to reflect flame impinging thereagainst toward the 85 front and side portions of the walls of said chamber.
24. A furnace comprising flame introducing means, a furnace chamber, and within 90 said chamber and in the path of the flame a flame distributor provided with a flame-dividing portion having above it an inclined reflecting facet, and on either side thereof vertical and inclined reflecting facets arranged to reflect flame impinging there- 95 against toward the front and side portions of the walls of said furnace.
25. A furnace comprising flame introducing means, a furnace chamber, and within 100 said chamber and in the path of the flame a pedestal having reflecting facets arranged to reflect flame toward the front and side portions of the walls of said furnace, the walls of said chamber toward the rear thereof having other reflecting facets.
26. The method of diffusing heat in furnaces, which consists in projecting a flame 105 jet into a furnace and in dividing said jet into bilaterally symmetrical streams and reflecting portions thereof backward and more 110 or less laterally and transversely of the direction of natural flow of the divided flame currents.
27. The method of diffusing heat in furnaces, which consists in projecting a flame 115 jet into a furnace, dividing said jet into bilaterally symmetrical streams, reflecting portions of each stream approximately transversely of the direction of natural flow of the divided flame currents, and re-reflecting 120 such reflected flame portions upward and toward the center.
- In testimony whereof I affix my signature, in the presence of two witnesses.
- JOHN F. MONNOT.
